UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 30,806, dated May 16, 1899.

Application filed April 6, 1899. Serial No. 712,018. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover, of which the following is a specification, reference being had to the accompanying drawings, forming part thereof, in which—

Figure 1 is a top or plan view of a manhole-cover embodying my design, and Fig. 2 is a cross-sectional view on the line $x-x$ of Fig. 1.

15 The views are deemed necessary and essential for the proper illustration of the design.

The main feature of my design for manhole-covers resides in the surface ornamentation and the configuration or outline of the 20 cover.

Referring to the drawings, a represents the body of the cover, which is cup-shaped and is circular or round in plan view. When viewed in plan, the cover has the appearance 25 of an annular ring or rim b , inclosing a field d of substantially circular outline. At two diametrical points of the cover and project-

ing into the field d from the annular rim b are arranged the two substantially oblong ornaments $f-f'$, the corners of which are rounded, 30 as at $f-f'$. The surface of each of these ornaments $f-f'$ is ornamented with a trefoil-like depression g , one of the points g' of which extends toward the rim b , while the other points are arranged at right angles to the 35 point g' and inclose a rounded bar-shaped ornament g^2 . The base of the cover when viewed in cross-section has a base h , which is inwardly bulged, as at h' , toward the center of the field d , and the inner and outer peripheries of the rim b are tapered, as at b^2 and b^3 , 40 in a downward direction.

Having thus described my invention, what I claim as new, and desire to secure by Letters Patent, is—

The design for a manhole-cover, substantially as herein shown and described.

In testimony whereof I have hereunto set my signature in the presence of two subscribing witnesses.

THOMAS P. GREGER.
